UNITED STATES PATENT OFFICE.

BERNARD T. LEVEQUE, OF BOSTON, MASSACHUSETTS, ASSIGNOR TO THE REECE
BUTTON HOLE MACHINE COMPANY, OF BOSTON, MASSACHUSETTS, A CORPORA-
TION OF MAINE.

BUTTONHOLE-STITCHING MACHINE.

1,179,116.

Specification of Letters Patent. Patented Apr. 11, 1916.

Application filed October 27, 1913. Serial No. 797,412.

To all whom it may concern:

Be it known that I, BERNARD T. LEVEQUE, a subject of the King of Great Britain, residing at Boston, in the county of Suffolk 5 and State of Massachusetts, have invented certain new and useful Improvements in Buttonhole-Stitching Machines, of which the following is a specification, reference being had therein to the accompanying drawing.

10 This invention relates to buttonhole stitching machines, particularly of that type known to the trade as the "Reece" buttonhole machine, wherein a stitch frame carrying the stitch forming mechanism on the 15 one hand and a work clamp or support on the other hand are relatively movable so as to enable the stitching to be carried along the sides of the buttonhole and around its end or ends. Such stitch forming mechanism 20 comprises usually an eye-pointed needle carrying the upper thread and below and opposed thereto the so-called "under sewing mechanism", which carries and operates an under thread in coöperation with the needle. 25 A sewing machine of this class is illustrated in my prior Patent, No. 1,019,677, dated March 5, 1912. Another is the Dixon Patent, No. 695,039, dated March 11, 1902. These prior patents will supply many 30 details and matters of description which may be, for convenience, omitted from the present application.

The main object of the present invention is to afford an under sewing mechanism of 35 efficient construction and operation and possessing the merit of simplicity and the advantages which pertain to simplified mechanism.

The further advantages hereof will either 40 be set forth in the hereinafter following description or will be obvious to those skilled in the art.

First will be referred to the preferred embodiment of the present invention as constituting an illustration of the same, and thereafter the novel features will be pointed out in the claims.

In the accompanying drawings forming a part hereof Figure 1 is a right-hand side 50 elevation of the front portion of a button-hole stitching machine embodying the present invention. Fig. 2 is a rear elevation of the under sewing mechanism detached. Fig. 3 is a right-hand elevation of the under sew-

ing mechanism. Figs. 4 to 7 show details 55 of the looper, Fig. 4 being a front view, Fig. 5 a section on the plane 5—5 of Fig. 4, Fig. 6 a section on the plane 6—6 of Fig. 4, and Fig. 7 being a diagram indicating the looper's movement. Fig. 8 is a front elevation 60 of the mechanism shown in Fig. 1. Fig. 9 is a top plan view of the under sewing mechanism.

Similar reference numerals designate corresponding parts in the several figures. 65

Certain parts are shown and may all be as in said Dixon patent, requiring therefore no detailed or other description except as follows, namely: the clamp frame 1, the casing 2 containing the needle bar 3, it 70 carrying an eye-pointed needle 4 for manipulating the upper thread, said needle bar and its casing being in practice mounted in the stitch frame already referred to but not herein shown, the curb or cam casing 5 in 75 practice secured to the movable stitch frame so as to travel with it under the clamp frame, said casing 5 having suitable adjustable headed bolts 6 which bear against smooth ways 7 at the under side of the 80 clamp frame, the rod 8 deriving its motion from a cam in the stitch frame, the cutter 9 and its carrying lever 10, the under thread needle 11, the carrier 12 therefor, the block 14, said block having the circular upper end 85 15 adapting it to receive at suitable times a circular movement, the gear 16 fast on a sleeve 17 extending from block 14, the tension device 18 for the under thread, the looper 19 and the throat plate 20; also the 90 circular ring-like portion 21 of the casing 5, which receives within it the circular upper end 15 of the block 14, and depending from said ring 21 a loop 22 having formed through it centrally at its lower end an 95 opening of such size as to loosely receive hollow hub 23 of gear 16, the gear being applied to the sleeve 17 and fixed there by a suitable nut 24.

The sleeve 17 has extended through it the 100 hollow rod or bar 25, said rod receiving through the opening in its lower end the second or underneath thread, such thread being passed upwardly through the rod 25 and into the under thread needle 11. The thread may pass out of the hollow rod 25 through an aperture 26, passing about the tension device 18 before passing to the under thread 105

needle 11. The rod 25 has fixed to it below the gear 16 a ball or enlargement 27, it being as herein shown embraced between two loose cup-shaped disks 28 and 29, both 5 loosely surrounding the rod 25 and contacting the ball 27, said disks being borne respectively upon the two forks 30, 31 of a lever 32 pivoted at 33 between two depending curved hangers 34, 34, these hangers 10 being connected in a suitable manner as by screws 35, with the loop-shaped depending portion 22 above referred to. The lever 32 is connected with the rod 8 as shown so that the cam operated movement of the rod 15 causes the oscillation of the lever 32 and thereby reciprocates upwardly and downwardly the hollow rod or bar 25.

In continuing the description of the machine illustrated in the drawings hereof, I 20 will refer to the new parts supplied by me and to the new arrangements and combinations of parts, during which reference will necessarily be made to parts which *per se* are not new herein but are for the first time 25 employed in the novel inter-relations and arrangements which I seek to cover.

The oscillatory seat or so-called block 14, which may take any physical form, I shall term the "stock", as it is merely a carriage 30 or frame for supporting the various working parts of the under mechanism. It shifts bodily, for example circularly, with all of the working parts supported by it, and these parts themselves move as may be required 35 for stitching more or less independently of the stock's shifting.

Generally speaking the under sewing mechanism hereof comprises in combination the movable stock referred to, and the 40 following elements supported by said stock, namely, the movable under needle carrier 12, the movable thread looper 19, the movable actuator or up-and-down reciprocating rod 25, which is adapted to be exteriorly 45 operated independently of the stock's shifting, and connections hereinafter to be more specifically described whereby said actuator actuates both said carrier and said looper.

Before describing the manner of actuation of the needle carrier and looper and the connections therefor, I shall refer to a convenient thread take-up or measuring contrivance shown herein, but which *per se* forms no part of the present invention. This 55 comprises a three-armed lever 36, 37, 38, pivoted at 39, the long arm 36 having at its extremity an eye or aperture for the thread, the arm 37 having a spring 40 for turning the lever leftwise in Fig. 8, and the lever's 60 oscillation being effected through a pin 41 on the up-and-down moving actuator rod 25. In order to adjust the movement of the lever an adjustable stop 42 is provided, a portion of which stands in the path of the 65 arm 38 to limit to any desired degree the

upward movement thereof. It will be understood that the carrier 12 is provided with a thread guide, for example as shown at 43, with which the looper arm 36 co-operates as in said Dixon patent.

The movement of the under needle carrier 12 is preferably a simple up-and-down swinging in the arc of a circle determined by the novel mechanism to be described, the needle first passing upwardly through the 75 buttonhole to a position above the fabric where it co-operates with the upper needle, the under needle then returning to a position beneath the fabric where it again co-operates with the upper needle, preferably 80 by the aid of the looper 19. The operation of the looper is not a simple swinging motion, but a compound motion consisting of the resultant of, first, an extended to-and-fro movement of the looper bodily between 85 the needle paths and, second, a slight lateral vibration serving to carry the barb of the looper around the path of the under needle. The purpose of such motion is that the looper may in moving toward the under 90 needle path take a loop of upper thread at each descent of the upper needle and present such loop to the under needle so that the latter may ascend through the loop causing an interlocking of the two threads.

Now will be described the following extremely simple trains of connections whereby the actuator 25 in its up-and-down movements effects actuation of the under needle carrier and also effects both motions of the 100 looper. Heretofore, as indicated in said prior patents, it has been deemed necessary to fit the needle carrier in a curved groove or race in order that its center of swinging might be sufficiently near the plane of the 105 work, yet without causing interference between the carrier fittings and other parts of the machine when the stock 14 shifts. According hereto, the objections and complications of such prior carrier fittings are obviated by the following simple construction. A relatively fixed bearing 50 upon the stock 14 is located as high as possible as indicated in Fig. 8, so that its axis is nearly 110 up to, but slightly under, the level of the 115 work. The bearing 50 may be inclined as shown in Fig. 3, as is usual in machines of this type. It is proposed herein to have the needle carrier swing simply in the arc of a circle about the bearing 50 as a center. To 120 this end there will be a hub member 51 engaging the bearing 50 and a spoke member 52 rigidly connecting the hub member with the carrier, so that the three constitute a single rigid device, simple in construction 125 and certain in its movements. To cause the carrier to swing upwardly and downwardly connections to the actuator may be employed comprising an intermediary or lever 53 having a relatively fixed pivot at the 130

right in Fig. 2 and oscillated upwardly and downwardly by a link 54 extending between the actuator 25 and the lever 53. Preferably the lever 53 swings in an inclined plane parallel to the plane of the carrier movement, as seen in Fig. 3; and consequently the link 54 should have, as shown, universal joints at its upper and lower ends. A link 55 extending from the free extremity of the lever 53 directly to the needle carrier at 12 completes the connections.

The looper 19 may take different forms, but is shown as hook-shaped, having a barb at its extremity, adapting it to operate as above stated. The looper may be detachably connected to a looper lever 60, and, as will be seen, this looper lever in the specific embodiment shown consists of three rigidly connected parts, 61, 62 and 63. The upper arm 61 of the looper lever is the part that carries the looper. The lower arm 62 of the looper lever constitutes a looper cam and its is proposed herein to effect both of the looper motions from this single cam. Between the upper and lower arms is a hollow member or frame 63, whose purpose is to take part in a universal pivot connection for the looper lever. Referring to Fig. 4, the looper and lever should swing substantially in a plane parallel to the paper for the purpose of the extended to-and-fro movement, and in a direction substantially normal to the paper for the slight lateral vibration of the looper. Such motions are permitted by the following pivotal connections. A fixed stud or axle 64, forming substantially a part of the stock, affords a bearing for a swinging axle 65, the latter in turn having a pivotal connection with the frame portion 63 of the looper lever. The described construction constitutes a simple and efficient universal fitting for the looper.

The looper movements are controlled by the cam 62. For this purpose a stud 66 is mounted on the actuator 25 and it has a spherical head 67 engaging in the groove 68 of the cam 62. The cam groove 68 is formed in the interior of the cam member and is provided with contours in two different planes as indicated in Figs. 4 and 5 respectively. Referring first to Fig. 4, the dotted line 69 indicates the path of relative movement of the sphere and cam. The first portion of this movement is a dwell, the ascending sphere then entering the inclined portion of the cam causing the entire looper lever to swing and moving the looper bodily toward the needles. The cross-section of Fig. 5 shows the transverse contour of the cam groove, the large diagram thereof in Fig. 7 indicates the curved path 70 of relative movement of the sphere in the cam. This indicates that as the sphere ascends it effects toward the end of the movement a slight lateral displacement and return move-

ment, this giving the desired resultant curved path to the looper to enable its barb to pass around and lie behind the path of the under needle. Thus the cam constitutes a single device operated by the movements of the actuator for giving to the looper both of its aforesaid movements. A convenient expedient is to render the outer half 71 of the cam 62 removable and detachable to permit the insertion of the spherical stud.

It will thus be seen that there has been described a buttonhole stitching machine attaining the advantages recited and other advantages will be apparent to those skilled in the art. Since many matters of design, arrangement, combination, detail and other features may be afforded without departing from the principles hereof, it is not intended to limit the invention to such features excepting in so far as the same are specified in the appended claims.

What is claimed is:

1. In a buttonhole stitching machine the combination of means for manipulating an upper thread and under thread mechanism comprising a shiftable stock, and the following elements carried on said stock, namely; a movable actuator exteriorly operable independently of the stock's shifting, an under needle carrier, a bearing relatively fixed on said stock in a position near to but slightly below the plane of the work, a hub member engaging said bearing, a spoke member rigidly connecting said carrier and hub member, and connections whereby the actuator actuates said carrier to swing about said bearing; and a looper actuated from said actuator to coöperate with said carrier, said looper mounted on a universal pivot device and connected to said actuator through a double acting cam device.

2. In a buttonhole stitching machine the combination of means for manipulating an upper thread and under thread mechanism comprising a shiftable stock, and the following elements carried on said stock, namely; a movable actuator exteriorly operable independently of the stock's shifting, an under needle carrier actuated from said actuator, a looper adapted to receive an extended to-and-fro movement and a slight lateral vibration, a looper lever on which the looper is rigidly connected, and a cam device operated by the movements of said actuator and having action in two different planes for giving both said movements to the lever and looper.

3. In a buttonhole stitching machine the combination of means for manipulating an upper thread and under thread mechanism comprising a shiftable stock, and the following elements carried on said stock, namely; a movable actuator exteriorly operable independently of the stock's shifting, an under needle carrier actuated from said

actuator, a looper fitted by a universal pivot device to receive an extended to-and-fro movement and a slight lateral vibration, and a member having a cam contour in two planes operated by the movements of said actuator for giving both said movements to the looper.

4. In a button-hole stitching machine the combination of means for manipulating an upper thread and under thread mechanism comprising a shiftable stock, and the following elements carried on said stock, namely; a movable actuator exteriorly operable independently of the stock's shifting, an under needle carrier actuated from said actuator, a looper, a looper lever carrying said looper and adapted to receive an extended to-and-fro movement and a slight lateral vibration, and a cam connection between said actuator and lever operated by the movements of said actuator for giving both said movements to the looper, said connection comprising a spherical stud on the actuator engaging a cam groove in the lever having a contour in two planes for producing the respective looper motions.
5. In a buttonhole stitching machine the combination of means for manipulating an upper thread and under thread mechanism comprising a shiftable stock, and the following elements carried on said stock, namely; a movable actuator exteriorly operable independently of the stock's shifting, an under needle carrier actuated from said actuator, a looper and a carrying lever therefor fitted by a universal pivot device to receive an extended to-and-fro movement and a slight lateral vibration, and a means operated by the movements of said actuator for giving both said movements to the looper; said pivot device comprising an axle mounted on the stock, and a swinging axle mounted on said first axle, said two axles located at substantially the same point in the length of the lever so as to constitute a gimbal.

In testimony whereof I affix my signature in presence of two witnesses.

BERNARD T. LEVEQUE.
